UNITED STATES PATENT OFFICE.

STACY B. HASELTINE, OF CHICAGO, ILLINOIS, ASSIGNOR TO WILLIAM H. MINER, OF CHAZY, NEW YORK.

DRAFT-YOKE FOR RAILWAY-CAR DRAFT-RIGGING.

1,369,654.

Specification of Letters Patent. Patented Feb. 22, 1921.

Application filed July 5, 1919. Serial No. 308,766.

To all whom it may concern:

Be it known that I, STACY B. HASELTINE, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of 10 this specification.

My invention relates to improvements in draft yokes for railway car draft rigging.

One of the objects of my invention is to 15 provide an efficient and simple draft yoke and one in which there may be a swinging relation between the yoke head and the yoke strap in order to permit the lateral movement of the draw bar in service. Other objects will appear from the description of 20 the device hereinafter following.

In the drawings forming a part of this specification, Figure 1 is a side elevation, part in vertical section, of a draft yoke embodying my invention. Fig. 2 is a plan view of the forward portion of said yoke. Fig. 3 is a part cross section taken on line 25 3-3 of Fig. 1. Fig. 4 is a perspective view of one of the blocks employed in said construction. Fig. 5 is a sectional view of a yoke head and the adjacent ends of the yoke strap illustrating a modification. And Fig. 30 6 is a vertical sectional view illustrating a further modification.

Referring to the drawings, the numeral 35 10 indicates a draw bar shown by the dotted lines in Fig. 1 of the drawings, 11 a yoke head, 12 a yoke strap having an upper arm 13 and a lower arm 14. The said yoke strap

40 is a one-piece member, the arms thereof having at their forward free ends the in-turned gibs 15, each of said gibs being of a T-head shape and being adapted to engage within the blocks 16 hereinafter described.

45 The yoke head 11 is of a general box-like form having a central longitudinal aperture to receive the draw bar 10, having its sides slotted, as at 17, for the passage of a coupler key and having in its top member 50 and in its lower member undercut openings 18 having enlarged circular under bearings 22 at their inner ends within which the blocks 16 are received. The blocks 16 are four in number, two being employed for each opening 55 18 in the yoke head. They are of the gen-

eral shape shown in detail in Fig. 4 of the drawing, having an arcuate edge 19 and an opposed edge provided with a shoulder 20. When the parts are in assembled position, as illustrated in Fig. 1 of the drawings, the blocks 16, one forwardly and one rearwardly arranged within the openings 22 about the gibs 15, secure the arm of the yoke to which said gib is attached within the yoke head. This is accomplished through the flange 21 60 upon the end of the gib which engages against the shoulders 20 upon the bearing blocks 16. When in its normal assembled position, the T-head of the gib is transverse to the axis of the yoke head. In disassembling, the yoke strap 12 is rotated sufficiently—as, for instance 90°—to place the same transversely to the axis of the yoke head, and when in this position the blocks 16 may be withdrawn after the yoke strap 65 70 has been slipped from the head through the openings 18 longitudinally provided in the upper and lower walls of the head and forwardly opening therein. In assembling the parts, the reverse of this operation is 75 employed. The construction provides a pivoted head upon the yoke strap 12 which permits its swinging in reference to the yoke strap on lateral movement of the draw bar 80 in train operation. When mounted between 85 the draft members of a car, the yoke and head cannot be accidentally or otherwise disassembled because the relative turning of the head and yoke strap will be insufficient for that purpose, but when dismounted 90 from the car, it will be apparent that the yoke strap and head may be readily assembled and disassembled.

Fig. 5 illustrates a modification which 95 differs principally from the structure shown in Fig. 1 in that the blocks in the aperture in the yoke head are each in one piece instead of two. Referring to Fig. 5, the numeral 30 indicates the upper arm of a yoke strap and 31 the lower arm thereof, only the 100 forward portion of said arms being shown in the figure. A yoke head is indicated at 32 having the sides 33 and top and bottom 34 and 35 respectively. The top and bottom each has an opening, as indicated at 105 36, and within each opening is mounted a single block 37 having a recess 38 therein, the said recess being provided with a T-head opening for the passage of the T-head in-turned gib of the adjacent yoke arm, said 110

gib being indicated at 39. Each of the said blocks 37 is circular in shape and is provided with a flange 40 engaging against the annular shoulder 41 provided upon the inner 5 face of the top and bottom portions of the yoke head. This prevents the passage of the block through the opening in the yoke head and permits the pivoting or swinging of the yoke head in reference to the yoke 10 arms. In disassembling the yoke strap from the yoke head the strap is turned sufficiently—as, for instance, 90°—to permit the withdrawal of the T-headed gibs from the blocks 37, through the slots 70 in the 15 head. When the coupler is withdrawn, the blocks may be removed from the interior of the yoke head. In assembling the yoke head and yoke strap, the reverse of this operation is employed.

20 In Fig. 6 a further modification is illustrated. In this modification, the numeral 50 indicates an upper yoke arm and 51 a lower yoke arm. The rear end of the yoke is indicated at 52, the intermediate portions 25 of the arm being broken away in the drawing. The yoke arms are separately made and when placed in assembled position are riveted together at their rear ends, as indicated at 53. 54 indicates a yoke head provided with the usual sides and having in the 30 top and bottom members 55 and 56, respectively, the openings 57—57. These openings are each adapted to receive a block 58, which is provided with a flange 59 seated against 35 the shoulders 60 provided on the interior faces of the top and bottom members of the head. The blocks 58 are circular in shape and are themselves provided each with an opening 61 having a forward inset portion 40 62 to receive an inturned forward end 63 of a yoke arm. The blocks 58 permit the swivel of the head upon the yoke strap. In assembling, the blocks 58 are inserted from the inner side of the yoke head into the 45 openings 57. The forward ends of the yoke arms are then inserted in the openings in the blocks 58 angularly, as indicated by the dotted lines in Fig. 6, showing the position of the upper yoke arm. The rear ends of 50 the yoke arms are then brought together, when the forward ends will assume the position in the blocks 58 as shown by the full lines and indicated by the numerals 64—64. The rear ends of the arms are then riveted 55 together, as indicated at 53, thus providing a headed yoke having a pivotal connection between the head and the yoke arms.

I claim:

1. In a yoke for railway car draft rigging, 60 in combination, a yoke strap, a yoke head and blocks, the yoke head having openings

to receive said blocks and the yoke strap having inturned T-headed gibs received in said blocks.

2. In a draft yoke for railway cars, in 65 combination, a yoke head having circular opposed openings therein, circular blocks within said openings and a yoke strap having T-heads at its free ends, the said blocks being provided with openings for the reception of said T-heads.

3. In a draft yoke for railway cars, in combination, a yoke head having opposed openings therein, a yoke strap having T-heads at its free ends and blocks mounted 75 in the openings in the yoke head, the said blocks being provided with flanges to prevent their outward movement through the openings in said head, and the said blocks being provided with openings to receive the 80 T-heads of the yoke strap.

4. In a draft yoke for railway cars, in combination, a yoke strap, a yoke head and blocks, the yoke head being provided with opposed openings to receive said blocks, the 85 yoke strap having ends received within said blocks, the blocks being provided with flanges to prevent their outward passage through the openings in the head, the yoke strap being provided with flanges engaging 90 the said blocks.

5. In a draft yoke for railway cars, in combination, a yoke strap and yoke head 95 swingingly mounted thereon, the yoke head being provided with openings and having blocks mounted in said openings, the said blocks being provided with openings to receive the ends of the yoke strap, the said ends of the yoke strap being provided with a T-head adapted to pass through openings 100 in the blocks in one position and to be held within said blocks in another position.

6. In a draft yoke for railway cars, the combination with a hollow yoke head adapted to receive a drawbar butt inserted 105 longitudinally therein; of yoke acting means having upper and lower arms separately formed from the head; and upper and lower pivotal connecting means, separable from both the head and said arms, said pivotal 110 connecting means having detachable shouldered interlocking engagement with the forward ends of said arms, said head having upper and lower shouldered openings for detachably rotatably receiving said pivotal 115 connecting means.

In witness that I claim the foregoing I have hereunto subscribed my name this 17th day of June, 1919.

STACY B. HASELTINE.
